ATTORNEY.

UNITED STATES PATENT OFFICE.

JOHN PFEIFER, OF PHILADELPHIA, PENNSYLVANIA.

SCOOP.

SPECIFICATION forming part of Letters Patent No. 340,816, dated April 27, 1886.

Application filed December 23, 1885. Serial No. 186,536. (No model.)

To all whom it may concern:

Be it known that I, JOHN PFEIFER, a citizen of the United States, residing in the city and county of Philadelphia, State of Pennsylvania, have invented a new and useful Improvement in Scoops or Shovels, which improvement is fully set forth in the following specification and accompanying drawings, in which—

10 Figures 1 and 2 represent views of opposite faces of a scoop or shovel embodying my invention. Fig. 3 represents a longitudinal section thereof. Fig. 4 represents a view of detached portions thereof.

15 Similar letters of reference indicate corresponding parts in the several figures.

My invention consists of a scoop or shovel of novel, strong, durable, and cheap construction, as will be hereinafter fully set forth.

20 Referring to the drawings, A represents the blade of a scoop or shovel, and B the handle thereof. The blade is formed of sheet metal, steel being preferred, stamped into proper shape, with a crimp, C, at the center of the back 25 of the rim thereof, and to said crimp is secured the handle B, which latter is constructed of metal of partial tubular form, the end adjacent to the blade being primarily riveted to said crimp C, and then welded thereto, (see 30 Fig. 4,) so that the handle and blade are comparatively integral.

D represents the pad of the scoop, the same being formed of metal, riveted or otherwise secured to the rim of the scoop at the rear of 35 the crimp C, and having its tang E extending for part of the length of the handle B at the rear thereof. Between a portion of the handle and the tang E and a portion of the pad D is a filling or stiffener, F, of wood, the same 40 being secured in position by means of rivets G, which pass through the handle, tang, and stiffener, thus firmly connecting said parts.

To the end of the handle B is secured the grip H, which consists of a yoke, J, having at one end the handle-piece K, and at the 45 other end a circular flange, L, which enters the adjacent end of the handle B, and is riveted thereto, thus firmly connecting the grip with the handle.

It will be seen that the handle, being metal, 50 partly tubular or crimped, is strong, light, durable, and cheap, and obviates the use of a wooden handle, which is liable to warp, splinter, &c. The tang of the pad forms a continuation of the peripheral curve of the tubular handle, thus avoiding the presentation of the edges of the tube to the hand of the workman. The wooden stiffener F increases the 55 strength of the scoop, especially at the place where the handle joins the blade and adjacent part of the handle without materially adding to the weight of the scoop.

In order to strengthen the rim of the shovel, especially at the upper end or back thereof, I corrugate said rim, the effect of which is evident; but the top and bottom edges of the rim are left non-corrugated, obviating scalloped or corrugated edges, while preserving the corrugations in the body of the rim.

Having thus described my invention, what 70 I claim as new, and desire to secure by Letters Patent, is—

1. A shovel or scoop having the blade A of sheet metal, with the crimp C, and having both the top and bottom edges of the rim uncorrugated or plain, substantially as described.

2. A shovel or scoop composed of a blade, A, of sheet metal, a hollow handle, a wooden stiffener extending from the blade along a portion of the handle, a pad, and a tang, the latter being secured to the handle and stiffener and connected with the pad, substantially as described.

3. A scoop or shovel composed of the blade A of sheet metal, having a crimp, C, substantially as described, a tubular handle, B, welded to said blade, and the pad D, secured to the rim of the blade, and having its tang E, extending along the back of the handle and conforming to the shape thereof, substantially as and for the purpose set forth.

JOHN PFEIFER.
